HEAT TRANSFER APPARATUS

Original application filed August 10, 1928, Serial No. 298,804. Divided and this application filed February 15, 1930. Serial No. 428,620.

The present invention relates to heat transfer apparatus and more particularly to apparatus of the character designed and adapted for the transfer of heat from one gas to another, as, for example, the heating of air for combustion by means of hot waste gases from a furnace.

As boiler pressures and furnace temperatures in steam plants have increased from time to time, the temperatures of the waste gases have correspondingly increased. As a result, there has been an increased demand in apparatus for abstracting and converting into useful work such waste heat or a substantial part of it. One type of apparatus has utilized such waste heat for the purpose of preheating the air supply for the combustion of the fuel in the furnace, and the principal object of the present invention is to provide a heat transfer apparatus especially designed and adapted for such use.

In this type of apparatus it is desirable to avoid, so far as possible, all leakage between the air and gas conduits or chambers, one way or the other according to the relative pressures. Where the pressure of the gas exceeds that of the air, any leakage will result in the admission of gases from the furnace into the air for combustion, with the resulting dilution of the latter and interference with the proper burning of the fuel. On the other hand, in the more common arrangement where the pressure of the air exceeds that of the gas, any leakage of air into the gas stream will result in a waste of power by the forced draft, air-handling fan, and a loss of stack draft through cooling of the gases by the lower temperature air.

One of the objects of the present invention is to provide a construction which, while facilitating the heating of the air by waste gases, and quick and easy removal and replacement of the parts subject to deterioration, will reduce to a minimum the liability of leakage in the apparatus.

Another object of the present invention is so to construct the air passages as to direct and control the flow of air through the apparatus so that a minimum expenditure of energy will be required for moving such air.

Still another object of the invention is to provide a construction in which the parts of the heater may be produced at a minimum cost of manufacture and assembling, with efficiency in operation.

With these and other objects in view, as will be apparent to those skilled in the art from the following description, the present invention consists in the heat exchange apparatus hereinafter described and more particularly defined in the claims.

In the accompanying drawings which illustrate what is now considered the preferred form of the present invention, as applied to an air heater for power plants, Fig. 1 is a side elevation of the heater showing the air and gas connections; Fig. 2 is a side elevation and Fig. 3 is a front elevation of one of the air chambers detached; Fig. 4 is a vertical section on line 4—4 of Fig. 2 looking toward the right, on an enlarged scale; Fig. 5 is a vertical sectional view on line 5—5 of Fig. 3 looking toward the right, on an enlarged scale, showing approximately the upper half of the chamber; Fig. 6 is a horizontal section on line 6—6 of Fig. 2; Figs. 7 and 8 are perspective views on a greatly enlarged scale, of certain details of construction; Fig. 9 is an enlarged perspective view of another detail of construction, namely, the channel members which are welded to the chambers at the inlet and outlet openings; Fig. 10 is a horizontal section on line 10—10 of Fig. 5 of the front portion of two adjacent air chambers in position in the heater; Fig. 11 is a similar view on line 11—11 of Fig. 5; and Fig. 12 is a detail, in vertical section, of the top front corner of the heater showing the chamber in position in the casing.

The heater illustrated in the accompanying drawings comprises briefly a shell or casing through which the hot waste gases pass from the bottom to the top through suitable inlet and outlet flues. Within the casing are located a plurality of thin air chambers or sections, closed on all sides to the gas and spaced slight distances apart from one another and from the casing to afford a large heat absorbing surface. Each chamber is provided at one end or edge with a top air inlet and a bottom

air outlet registering respectively with the air inlet and air outlet openings or flues in the front wall of the casing. The air is forced or drawn through the air chambers by means of a fan or other suitable draft producing means, absorbing heat from the gases through the chamber or section walls.

Referring to Figs. 1 and 12 of the drawings, the casing 11 is constructed of sheet metal secured together by bolts or rivets or in other suitable manner and is supported upon the horizontal I-beams 12. At the bottom of the casing is the gas inlet connection 13 for the hot gases, while at the top is the outlet connection 14 through which the gases escape to the stack. The back panels 15 are made removable for purposes of inspection and repair.

In the front wall of the casing are the air inlet and air outlet connections 16 and 17, respectively, through which the air for combustion is conducted to the air heater and thence to the furnace. It will be noted that the air inlet and outlet are identical in size and symmetrically disposed in the front wall of the casing.

Within the casing are located the thin or narrow air chambers or sections 19. These sections comprise flat side walls 21 and 22 (see Fig. 4) spaced a short distance from one another, one of the walls being bent or offset at its top, bottom and rear margins 23, and welded to the other wall as shown at 24 (see Fig. 6). By making one of these walls flat throughout its extent and giving the proper bend or offset to the margin of the other wall, a minimum of handling and work is required with corresponding minimum cost of manufacture.

In order to space the walls properly from one another, angle iron separators 26 (see Fig. 6) are spot welded to the walls. The middle portion of the front edge of each air chamber or section is similarly closed by bending the margin of one wall and welding it to the other one as shown at 28 (Fig. 2).

The air inlet and air outlet openings at the top and bottom of the front edge or end of the air chambers, which are of the same size and symmetrically positioned, are formed as follows: The side walls at these portions are cut to extend slightly beyond the intermediate portion and both are extended parallel to one another without bending, as shown at 30 in Fig. 10. At the extremity of each air opening are welded filling pieces which not only close the ends of these openings but provide a support or base for the studs by means of which the air chambers or sections are secured to the front wall of the casing. Thus, at the upper end of the inlet opening is located the block 35 (see Fig. 7) the end of which is bevelled as at 36 to fit the bevelled or bent over margin of the side wall at this point. This block is provided with a threaded open-

ing 37 in which is secured a stud 38 (see Fig. 5). A similar filling piece is welded in the bottom end of the outlet opening of the chamber.

The filling piece for the bottom of the inlet opening and the top of the outlet opening is shown in Fig. 8 at 39, and is provided with a similar stud-receiving opening 40 for the stud 41 (see Fig. 5). Both of the filling blocks have bevelled front edges 42 to provide a groove or space for the welding material.

Secured to each chamber at the inlet opening and also at the outlet opening is a channel piece or member 44, shown (in part) in enlarged perspective in Fig. 9. This member is formed with a long narrow slot 46 extending throughout nearly the length of the member but leaving at each end a solid portion 48 provided with an opening 50 to receive the securing studs 38 and 41. The free marginal portions of each side wall of certain of the channel members are bent over as shown at 52 in Fig. 9, to form beads or grooves. The other channel members are provided with straight marginal portions, as shown at 54 in Figs. 10 and 11.

The channel members are secured at the inlet and outlet openings, the front margins of the walls at each side of the openings passing through and fitting closely within the slot or opening 46 in the channel member as shown in Fig. 11, the parts being welded as indicated at 56.

When the chambers are assembled those having channels with hooked or beaded margins are alternated with chambers in which such margins are straight, as shown in Fig. 11. Thus the side walls of adjacent channel members have their faces in contact with one another, and in addition, the rear edge or margin of one is received in the bead or groove of the other, thereby preventing leakage between the chambers.

As an additional precaution, cement may be applied to the bead or groove to seal the joint between the parts, as indicated at 60.

The chambers are secured to the casing at their front edges by means of the studs 38 and 41 which pass through horizontal slots in the front wall of the casing immediately above and below the inlet and outlet openings. Nuts 66 on the studs draw the sections tight against the front wall of the casing with the solid end portion 48 of the channel member 44 making a tight joint between the chambers and the casing.

The sections are spaced apart and held from expansion at their middle portion by means of the vertical angle strips 68 welded to the outside of the chamber and positioned to contact with the side wall of the adjacent chamber.

The chambers are forced into close lateral engagement at their front edges in any suitable manner, as by jack-screws, the nuts 66

being loose at the time so that the studs 38 and 41 may slide along the slot in the front wall of the casing. Ordinarily one or two chambers at a time will be inserted in the casing and forced laterally into close engagement with the chambers already in position. As the chambers are forced successively into close contact with the chambers already inserted, these nuts 66 will be tightened to hold them in position while the next chamber is inserted and forced into place.

In order to avoid crushing of the chambers when this lateral pressure is applied at their front edges adjacent the inlet and outlet openings, the pressure blocks 69 have been welded in such openings.

To insure the effective utilization of all portions of the air chamber or section and prevent eddies and dead spots, a series of baffles 70 have been provided in the interior of the chamber adjacent the inlet and outlet thereof. These baffles are formed of sheet metal bent in the arc of a circle and welded to one side of the chamber and are so located that they turn the incoming air from a horizontal to a vertical direction and the outgoing air from a vertical to a horizontal direction, while maintaining a substantially even distribution of flow through both the inlet and outlet and the body of the air chamber.

In operation with the waste gases from the furnace passing upwardly through the casing, the air for combustion will enter through the inlet conduit 16 and after passing through the air chambers or sections will be discharged through the outlet conduit 17. Owing to the thinness of the air chambers or sections the streams or currents of air passing therethrough will be heated quickly to a high temperature. Preferably the counter flow principle will be employed, as above described, so as to maintain the maximum temperature difference between the gases and the air throughout the passage of the latter through the air heater.

The external surface of the air chamber being substantially straight and smooth, offers a minimum of resistance to the passage of the gases and at the same time, owing to the large surface area exposed to their action, quickly give up their heat to the walls of the chamber and thence to the air within.

If the chambers become corroded on their external surfaces adjacent the upper or cold end of the heater, it will not be necessary to discard such chambers but merely to reverse them upside down, making what was the top or cold end the bottom or hot end, where little or no further corrosion would occur, and bringing fresh uncorroded portions to the top. Such reversal is easily effected by removing the panels 72 at the back of the casing, and removing the nuts 66 on the studs 38 and 41 on the front of the sections. The sections

may then be separated laterally and one or more withdrawn from the back, and since they are alike at the top and bottom, both as to location and size of air opening and position of the studs, they may be re-inserted in inverted position and then clamped together and secured as before.

While the present invention has been described as embodied in an apparatus particularly designed and adapted for use as an air heater, it is to be understood that the invention is not necessarily limited thereto but may be embodied in other forms and constructions and used for other purposes.

This application is a divisional application of my pending application Serial No. 298,804, filed August 10, 1928.

Having thus described the invention, what is claimed is:

1. A heat transfer apparatus having, in combination, a casing having provision for conducting hot gases thereto and therefrom, inlet and outlet openings in the casing for the gases to be heated, a series of chambers in the casing spaced apart from one another and having inlet and outlet openings adapted to register with the inlet and outlet openings in the casing, and being provided with flanges adjacent their inlet and outlet openings, certain of the flanges having a groove, the flange of one chamber engaging the groove on the flange on the adjacent chamber to close the space between said chambers.

2. A heat transfer apparatus having, in combination, a casing having provision for conducting hot gases thereto and therefrom, inlet and outlet openings in the casing for the gases to be heated, a series of chambers in the casing spaced apart from one another and having inlet and outlet openings adapted to register with the inlet and outlet openings in the casing, and being provided with flanges adjacent their inlet and outlet openings, certain of the flanges having a groove, the flange on one chamber having surface engagement with the flange of the adjacent chamber and the edge of one flange fitting into the groove on the other flange to close the space between the chambers.

3. A heat transfer apparatus having, in combination, a casing having provision for conducting hot gases thereto and therefrom, inlet and outlet openings in the casing for the gases to be heated, a series of chambers in the casing spaced apart from one another and having inlet and outlet openings adapted to register with the inlet and outlet openings in the casing, and being provided with flanges adjacent their inlet and outlet openings, certain of the flanges having their margins turned back to form grooves, the edge of the flange of one section entering the groove in the flange of the adjacent section, the groove being adapted to receive cement

to seal the joint between the flanges and close the space between the chambers.

4. A heat transfer apparatus having, in combination, a casing for hot gases, inlet and outlet openings in the casing, a series of thin, hollow air chambers mounted in the casing, said chambers comprising flat parallel walls connected at their margins discontinuously to form air inlet and air outlet openings, a 10 filler piece secured within each chamber between the side walls thereof at each end of said openings and having provision for attachment to the casing, and members secured to the outside of the chambers adjacent the 15 openings for closing the spaces between the chambers.

5. A chamber for heat transfer apparatus comprising a pair of substantially rectangular flat parallel side walls welded to each 20 other at their margins to form a thin, hollow air chamber having air inlet and air outlet ports at one edge, and a series of short curved baffles for changing the direction of flow of air through the chamber, the series being 25 obliquely disposed to the direction of flow of air.

6. A chamber for heat transfer apparatus comprising a pair of substantially rectangular flat parallel side walls with inlet and outlet 30 openings at one edge, and two disconnected series of short curved baffles obliquely disposed, one opposite the inlet opening and the other opposite the outlet opening for changing the direction of flow of the air 35 through the chamber.

7. A chamber for heat transfer apparatus comprising a pair of flat parallel side walls, one of said walls having flat marginal portions and the other having its marginal portions offset and welded to the other wall to 40 form a thin, hollow air chamber having inlet and outlet openings at one edge, trapezoidal shaped filling pieces secured between the walls at the outer ends of the openings, and rectangular filling pieces secured between the walls at the inner ends of said openings.

8. A chamber for heat transfer apparatus comprising a pair of imperforate flat side walls united discontinuously at their edges 50 to form a thin hollow air chamber with an air opening at the edge, and having a pressure block secured in said opening.

9. A chamber for heat transfer apparatus comprising a pair of flat parallel side walls 55 with an opening at one edge and an apertured flanged member secured to said edge with its aperture in alignment with said opening, one of the flanges on said member being provided with a groove adapted to receive the flange 60 of the member of an adjacent chamber.

10. A chamber for heat transfer apparatus comprising a pair of flat parallel side walls 65 united at their edges to form a hollow air chamber and having an opening at one edge, a filler piece secured between the walls of the

chamber at each end of the opening, and an apertured flanged member having its aperture in alignment with said opening and overlying at each end the filler pieces.

11. A chamber for heat transfer apparatus 70 comprising a pair of substantially rectangular flat parallel side walls with inlet and outlet openings at one edge, and a series of spaced short curved baffles for changing the direction of flow of air through the chamber and for distributing the air evenly over the 75 surface of the chamber, the air being free and unrestrained adjacent the baffles.

12. A chamber for heat transfer apparatus comprising a pair of substantially rectangular flat parallel side walls with inlet and outlet 80 openings at the edge, and a series of uniformly spaced short curved baffles for changing the direction of flow of the air through the chamber.

In testimony whereof I have signed my 85 name to this specification.
